WINDING APPARATUS

Odell T. Brown, Old Hickory, Tenn., assignor to
 E. I. du Pont de Nemours & Company, Wil-
 mington, Del., a corporation of Delaware

Application August 1, 1940, Serial No. 349,074

10 Claims.

(Cl. 91—51)

This invention relates to the winding of yarn into a package, such as a cone or cop. More particularly, it relates to a means of applying an oil, or other treating liquid, in a satisfactory, uniform manner to a yarn as it is being wound into such a package.

In the winding of yarn on to a cone, it is customary to condition or lubricate the yarn during the winding operation in order to improve the running qualities of the yarn in this and subsequent operations.

However, the application of the oil or other liquid to the yarn in a satisfactory, uniform manner has proven difficult. In a winding machine, the core upon which the yarn is to be wound is frequently mounted upon a spindle that is driven at a constant speed throughout the entire winding operation. Hence, the linear speed of the yarn being wound upon the cone increases as the package is built up. The increase in speed of the yarn from start to finish is dependent upon the size of the yarn package formed, and in some cases, the speed increases 400%, or even more. Thus, to apply the oil uniformly to all parts of the yarn being wound upon the cone, it is necessary to so adjust the rate of application of the oil as to compensate for this increase in speed of the yarn.

It is an object of the present invention to provide an improved means for regulating the quantity of liquid applied to a yarn during the winding operation.

It is also an object of this invention to provide a means of continuously applying a regulated quantity of liquid to a yarn.

Other objects of the invention will appear hereinafter.

The objects of the invention are accomplished, in general, by passing the yarn, during the winding thereof, into contact with the flat, end face of an oiling disc which is rotating in an oil bath, and continuously increasing the chord of contact of the yarn with the disc face as the speed of the yarn increases. Throughout the specification any reference to the face of the oiling disc refers, of course, to the flat, end face thereof as distinguished from the circular edge of the disc since it would be impossible to increase the chord of contact of the yarn with the circular edge thereof.

The following written description of the invention will be more readily understood if taken in connection with the accompanying illustrations wherein:

Figure 1 is a front elevational view of the yarn 55 is gradually reduced. The yarn is then passed

winding positions of a winding machine embodying the present invention.

Figure 2 is a side elevational view, with parts shown in section, of a winding machine embodying a device constructed according to the principles of the present invention.

Figure 3 is a plan view, showing in detail, one means whereby the motion of the traverse back is utilized to control the movement of the yarn 10 over the surface of the oiling device.

Figure 4 is a plan view, showing in detail, another means whereby the motion of the traverse back may be utilized to control the movement of the yarn over the surface of the oiling device.

Figure 5 is a side elevational view, with parts shown in section, of a winding machine fitted with a modified form of the present invention.

Referring to Figures 1 and 2 of the drawings, reference numeral 11 designates a yarn drawn from a supply package 13. Numerals 15 and 17

designate fixed yarn guides which may be fixed to the frame of the machine or to the oil tank 25. Numeral 19 designates an oiling disc which is positioned for rotation within the oil tank 25.

25 The disc 19 is mounted on rotatable shaft 21, and may be fastened to said shaft by means of a set screw or the like positioned in shoulder 23 of the disc 19. A movable yarn guide 27 is positioned above fixed yarn guides 15 and 17.

30 The oiling disc 19 is positioned between yarn guides 17 and 27 in such a manner that the face of the oiling disc will be maintained in contact with the yarn 11 between these two guides. A yarn tensioning device 41 is positioned above movable

35 yarn guide 27 and a fixed thread guide 42 is positioned above the yarn tensioning device. The yarn tensioning member may be of any desired type; however, preferably a yarn tensioning member of the type disclosed in the copending application of Arthur E. Guenther, Serial No.

40 309,653, filed May 24, 1938, now U. S. Patent No. 2,223,912, is used for imparting of a tension to the yarn. The yarn tensioning member of the above-said Guenther patent comprises a flexible

45 pinch tensioning blade which is connected by linkage elements to a pivoted yarn traversing mechanism. As the diameter of the yarn package increases, the yarn traversing mechanism moves about its pivot point and thereby shifts

50 the linkage elements to decrease the tension on the yarn by reason of the pressure of the flexible pinch tensioning blades. As the yarn builds up on the package and the linear speed of the yarn being wound increases, the tension on the yarn

55 is gradually reduced. The yarn is then passed

over a yarn bail guide 43 which is positioned above fixed yarn guide 42. The yarn is then passed through reciprocating yarn guide 45 which is mounted for reciprocation in the pivoted traverse back 35 in a known manner. The reciprocating yarn guide 45 traverses the yarn while it is being wound on a rotating yarn package 47. The yarn package 47 is wound on a yarn supporting member 48 mounted on a spindle 49 which is rotated at a constant speed.

The movable yarn guide 27 is mounted on a system of levers 29, which levers are pivoted at 31 to the arm 32 which is fixed on the weight 33. The weight 33 is integral with the pivoted traverse back 35. The traverse back and weight are pivoted at 37 to the frame 39 of the winding machine.

The operation of the winding apparatus shown in Figures 1 and 2 is substantially as follows: The yarn 11 is drawn from the fixed package 13 and is passed upwardly through fixed yarn guides 15 and 17. The yarn is then passed across the face of oiling disc 19, which disc is continuously rotated within oil tank 25. The oil, or other thread size or finish, is transmitted to the yarn from the disc 19, and the yarn is maintained in contact with the disc by fixed yarn guide 17 and movable yarn guide 27. The movable yarn guide 27 is progressively moved during the winding operation in such a manner that the yarn will gradually contact an increasingly large surface of the oiling disc 19. This is clearly illustrated in Figure 2 of the drawings. The yarn, at the beginning of the winding operation, contacts the disc over the chord A-B. As the yarn builds up on the package, the movable yarn guide is gradually shifted so that at the end of the yarn winding operation the yarn cuts across disc 19 over the chord C-D. The lever members 29 which connect the movable yarn guide 27 to the pivoted weight 33 are adapted to shift the yarn guide as the weight 33 is shifted about pivot 37. The yarn is passed through tensioning device 41, thence through fixed yarn guide 42 over bail guide 43 and through the reciprocating yarn guide 45 which is maintained in contact with the yarn package being wound and traverses the yarn back and forth across the package as the package is rotated.

Referring to Figure 3 of the drawings, the movable yarn guide 27 is shifted in the direction of the arrow positioned adjacent thereto and through the following leverage mechanism: Lever arm 51 is pivotally mounted in the pivoted traverse back weight 33. As the weight 33 is shifted in the direction of the arrow positioned adjacent thereto, the lever arm 51 is drawn along with the weight, thereby transmitting a pull on the bell-crank arm 57. The arm 51 is pivoted to bell-crank arm 57 at one of the positions 55. The arm 51 is provided with a pivot connection 53 which connects the same to bell-crank arm 57. The bell-crank arm 57 transmits an upwardly directed movement to rod 65 through the slot 61 of the bell-crank lever and pin 63 connected to the rod 65. The pivot point of the bell-crank lever is fixed by means of arm 59. The rod 65 is adapted to slide in an opening in member 67. The member 67 is rigidly attached to the framework 69 of the winding machine. It is thus readily apparent that the yarn will be shifted in the manner shown in Figure 2 by means of the leverage mechanism shown in Figure 3, and the shifting is controlled by the motion of the counterweight 33 as the yarn package builds up. Thus, a linear

relationship is maintained between the increase in speed of the yarn and the increase in surface contact by the yarn of disc 19.

Referring to the modified form of leverage mechanism for movement of the movable yarn guide 27, shown in Figure 4 of the drawings, the yarn guide 27 will be shifted in the direction of the arrow positioned adjacent thereto upon movement of the counterweight 33 in the direction of the arrow shown at that point. The lever member 71 is pivoted to counterweight 33 at one end thereof. At the other end thereof the lever member 71 is pivoted at 73 to the curved lever arm 75. The lever arm 75 is pivotally mounted at 85 on fixed arm 81. The arm 81 is fixed to the frame 82 of the winding machine by means of bolts 83. The lever arm 87, which is connected to the movable yarn guide 27, is pivoted at 85 to the curved lever member 75. The lever arm 87 is adapted to pass through an opening in the angularly disposed element 89 fixed to the rigid member 81.

As the counterweight 33 shifts in the direction of the arrow, arm 71 pulls arm 75 about pivot 79 and thereby pulls downwardly on arm 87 which is pivoted to the oppositely disposed end of arm 75. The movable yarn guide 27 is thus moved downwardly in the direction of the arrow adjacent thereto.

Referring to the modification shown in Figure 5 of the drawings, the movable yarn guide 27 is mounted for vertical movement, instead of horizontal movement, as shown in Figure 2 of the drawings. It will be readily apparent that the movable yarn guide 27 may be moved either vertically or horizontally to gradually increase the surface contact of the yarn with the oiling disc as the speed of the yarn increases due to increase in build up on the yarn package. The movable yarn guide 27 may be moved vertically by connecting between the yarn guide 27 and the counterweight 33 a leverage system similar to that illustrated but connected to the counterweight at an angle of 90° in the manner in which the leverage mechanism illustrated is connected to the counterweight.

It will be obvious that any other type of leverage mechanism commonly employed to transmit the substantially straight-line motion to the movable yarn guide may be employed in place of the leverage mechanism as specifically disclosed herein. It is furthermore obvious that both the direction and extent of motion of the movable yarn guide 27 is dependent upon the adjustment of the system of leverage members, and the invention contemplates any adjustment that is necessary to permit the desired movement of the movable yarn guide as the yarn package is increased in size. In accordance with the specifically illustrated apparatus the yarn guide 27 is made movable and the yarn guide 17 is maintained stationary, so that the yarn between these two guide members will be caused to have an increasing surface contact with the oiling disc. Obviously the yarn guide 27 may be maintained stationary and yarn guide 17 moved for the same purpose. Furthermore, if desired, both guides 17 and 27 may be made movable to gradually increase surface contact of the yarn with the oiling disc.

According to the preferred method of operation of the apparatus, the oiling disc 19 is rotated at a constant speed. If desired, however, speed of rotation of the disc may be varied, as the speed of the yarn increases to pick up an increasingly greater quantity of oil. That is, if the movement of the yarn guide or guides, as described

above, does not sufficiently compensate for the increase in speed of the yarn as the package is built up, satisfactory compensation may be obtained by increasing the speed of rotation of disc 19 as the speed of the yarn increases.

Although the invention has been illustrated and described in connection with a winding machine of the type manufactured by the Universal Winding Company, the invention is not limited to this type of winding machine and may be used to advantage on any type of winding machine in which the speed of the yarn increases as the yarn package is built up.

This invention provides a means of applying an oil or other treating liquid in a uniform manner to a yarn being wound upon a winding machine, the invention providing a means for compensating for the increased speed of travel of the yarn as the yarn package is built up.

The device contemplated by this invention provides for a greater length of contact between the yarn and the oiling device than has been possible with previous devices. Hence, a vibration of the yarn passing over the surface of the disc does not result in so large a variation in the amount of oil applied to a given length of yarn.

In passing over the oiling surface of the disc, the yarn is preferably displaced from its normal path between the thread guides 17 and 21 by a distance equal to one-half the width of the disc, or about $\frac{1}{8}$ of an inch, since the disc is centered on the normal line of travel of the yarn. This displacement of the yarn causes the application of a slight tension which acts to hold the yarn tightly to the surface of the disc. This tension acts to further reduce the vibration of the yarn against the surface of the disc and thus aids the uniform application of oil to the yarn. This vibration of the yarn against the surface of previously known cylindrical wipers contributes to the non-uniform application of oil to yarn obtained by the use of such a device.

Since, according to this invention, the yarn wipes oil from a vertical surface, any loose or broken ends of yarn fall from the surface of the wiper to the hub or shaft of the device where they do no harm and may be easily removed. In the case of a cylindrical type of wiper, these loose yarns tend to form wraps about the surface of the wiper and thus interfere with the satisfactory operation of the device. In the removal of such wraps, the surface of the wiper is often scratched. These scratches cut and abrade the yarn passing over the wiper and great care must be taken to insure their removal. As mentioned above, such wraps cannot form on the wiper surface of the disc member constructed according to the principles of this invention. This constitutes a further great advantage of this device over the devices known to the prior art.

The device contemplated by this invention is less expensive than other devices constructed for this purpose. The device is easier to adjust for various size packages of yarn and does not require so accurate a setting as do devices of other types. Hence, the maintenance costs of such a device are also low.

Since it is obvious that many changes and modifications can be made in the above-described details without departing from the nature and spirit of the invention, it is to be understood that the invention is not to be limited to the described details except as set forth in the appended claims.

I claim:

1. In a yarn winding apparatus of the type in

which the linear speed of the yarn increases as the yarn package increases in circumference, an oiling disc, means for passing the yarn in contact with the flat, end face of said oiling disc, and means for gradually increasing the surface of contact of the yarn on said disc.

2. In a yarn winding apparatus of the type in which the linear speed of the yarn increases as the yarn package increases in circumference, a circular oiling disc, means for passing the yarn in contact with the flat, end face of said oiling disc, the yarn at any instance describing a chord on the circular face of said disc, and means for gradually increasing the chord of contact of the yarn on said disc.

3. In a yarn winding apparatus of the type in which the linear speed of the yarn increases as the yarn package increases in circumference, an oiling disc, a pair of yarn guides for passing the yarn in contact with the flat, end face of said oiling disc, at least one of said yarn guides movable to gradually increase the surface of contact of the yarn on said disc.

4. In a yarn winding apparatus of the type in which a linear speed of the yarn increases as the yarn package increases in circumference, an oiling disc, a pair of yarn guides for passing the yarn in contact with the flat, end face of said oiling disc, one of said yarn guides being stationary, and the other of said yarn guides being movable to gradually increase the surface of contact of the yarn on said disc.

5. In a yarn winding apparatus, a winding spindle, a traverse frame back pivoted to move away from said spindle as the yarn package increases in diameter, an oiling disc, and means connected to said traverse frame back for gradually increasing the surface of contact of the yarn on flat, end surface of said disc.

6. In a yarn winding apparatus, a winding spindle, a traverse frame back pivoted to move away from said spindle as the yarn package increases in diameter, an oiling disc, a pair of yarn guides for passing the yarn in contact with the flat, end face of said oiling disc, and means connected to said traverse frame back for moving at least one of said yarn guides to gradually increase the surface of contact of the yarn on said disc.

7. In a yarn winding apparatus, a winding spindle, a traverse frame back pivoted to move away from said spindle as the yarn package increases in diameter, an oiling disc, a pair of yarn guides for passing the yarn in contact with the flat, end face of said oiling disc, one of said yarn guides being stationary, and means connected to said traverse frame back for moving the other of said yarn guides to gradually increase the surface of contact of the yarn on said disc.

8. In a winding machine, means for winding a package, means for tensioning a strand of yarn feeding to the package, a container for liquid, a rotary contact disk partly submerged in the liquid, means for guiding the strand across the radial face of the contact disk, and means actuated by the increase in diameter of the winding package to progressively shift the strand toward the axis of the contact disk to increase the extent of its contact therewith.

9. In a winding machine, the combination of a winding spindle, a thread-guide for traversing yarn on the spindle to wind a package, a traverse-frame for supporting the thread-guide to adapt it to move away from the winding spindle during the growth of the package, a wetted con-

tact disk for moistening the yarn, means for guiding the yarn across the radial face of the contact disk, and means actuated by the movement of the traverse-frame during the growth of the package to operate the guiding means to shift the strand toward the axis of the contact disk to progressively increase its extent of contact therewith.

10. In a winding machine, the combination of

means for winding a package, a container for liquid, a rotatable disk arranged to dip into the liquid in said container, means for guiding a strand across the radial face of the contact disk, and means actuated during the winding of a package to shift the strand radially inward on the face of the contact disk to increase its extent of contact therewith.

ODELL T. BROWN.
